UNITED STATES PATENT OFFICE.

ERNEST SYDNEY, OF LONDON, ENGLAND, ASSIGNOR TO JAMES ROBINSON & SONS (ROMILEY) LTD., OF STOCKPORT, ENGLAND.

HYDRAULIC AND OTHER PRESSES.

Application filed July 2, 1926, Serial No. 120,102, and in Great Britain October 1, 1925

This invention has reference to hydraulic and other presses used in the manufacture of various articles, more particularly hats, and is applicable to such presses whether the hats 5 to be produced are of the stiff, hard, flexible or soft kind; the invention having for its object the provision of means for ensuring the safety of the operator in the event of fracture or derangement occurring in a holding part of the press during the working thereof; a further object being to prevent damage to other parts of the machine.

According to this invention the upper or vertically movable plate of the press is provided with lugs or brackets which are adapted to engage the lever or handle, whereby the plate is freed or manipulated, in such a manner as to lock or hold the same. The said lever or handle is mounted rotatively in relation to the plate and has one or more arms, one of which is adapted to serve as the operative handle. One or more of the lugs or brackets may carry a spring against which the lever or handle is moved in operating the same and by which it is automatically returned and secured upon the attendant releasing the said lever or handle, the arrangement being such that the lever or handle obtains a bearing or position of lock in relation to a fixed part of the press which is suitably formed or adapted for its reception. Such fixed part may conveniently be one of the press guides or supports.

In order that the invention may be readily understood and carried into effect same will now be more fully described with reference to the accompanying drawings in which:—

Figure 1 is an elevation of a portion of a hat press sufficient to illustrate the application thereto of the present invention.

Figure 2 is a corresponding plan.

Figure 3 is a side view of the spring carrying lug or bracket detached from the vertically movable plate.

Figure 4 is a side view of one of the lugs or brackets for general use with the spring carrying lug or bracket.

Figure 5 is a plan view of the mode of mounting the lever or arm in the spring carrying lug or bracket.

Figure 6 is a plan view illustrating a modification of the safety device.

a indicates the upper or vertically movable plate of the press and *b* the operating lever or handle rotatively and concentrically

mounted in relation thereto. The said lever is constituted by the central boss *b*¹ and radial arms *b*² one of which latter carries the handle *b*. The plate *a* is provided with lugs or brackets, *c*, *c*¹, *c*², which are adapted to engage the lever or handle in such a manner as to lock or hold the same. The lug or bracket *c* in the construction illustrated carries a spring *d* against which the lever or handle is moved in operating the same and by which it is automatically returned upon release thereof by the attendant so that it becomes automatically secured or held by obtaining a bearing or position of lock in relation to or on a fixed part of the press. In the arrangement shown this position is on one of the press guides or supports *e*. These guides or supports usually extend upwardly beyond the press plates and one serves as an abutment for the lever or handle arm. With the present invention there is no necessity for these guides to project above the plates and it will be seen that their upper ends serve as bearers for the outer ends of the arms *b*² when the press is open. If desired however one of the said guides may be stopped off at the level of the top of the press while the other of the guides may be as ordinarily constructed the arms *b*² other than that pertaining to the handle *b* being of a length which allows of their working within the said guides as will be readily understood, while the arm with the handle *b* is the one which passes on to the upper end of the stopped-off guide or support so as to assume a position of rest thereon.

The brackets *c*¹ and *c*² may be simply of strap or cranked form as shown clearly in Figure 4 and be secured to the plate *a* by screws or bolts (not shown). The bracket *c* which carries the spring *d* is elongated and provided with a sliding rod *f* on which the spring is coiled, the said rod being screwed or otherwise secured to the arm *b*² pertaining to the handle *b*, so that the rod projects laterally from the said arm. The rod may however be secured to a block *g*, (Figures 3 and 5) having the opening for the arm *b*² formed with curved contact faces so as to allow of the longitudinal displacement of the arm relatively to the bracket incidental to the angular movement of the lever *b*. The spring *d* thus bears at one end against the arm or the block and at the other end against the depending part of the bracket through which the rod *f* slides there being a washer *h*

on the inner side of the depending part to receive that end of the spring.

In Figure 6 an alternative form of bracket *c* is shown wherein the elongation is curved 5 to conform to the arc incidental to the angular movement of the lever or handle *b*, the rod *f*, being similarly curved. The block *g* in this arrangement may or may not be formed with curved faces for contact with 10 the arm *b*² and obviously the rod *f*^x may be secured directly in the arm *b* as will be readily understood from an inspection of the figure now referred to.

Although in describing the carrying out of 15 the invention reference has been made to stopping-off one or more of the guides or supports *e* a similar effect may be obtained by shortening the chain *i* whereby the upper or movable plate *a* is held so that the arm may 20 be positioned on the top of the guide pillar or support adjacent thereto the height of the said guide in that case not necessarily being reduced.

It will be apparent that the operation of 25 the device is such that the spring *d* tends to force the handle *b* and arm *b*² pertaining thereto into a position of safety over the guide pillar *e* adapted for its reception.

In closing the press the lever or handle *b* 30 is turned through a small angle to permit the lowering of the plate *a* and after the press has been opened by raising the said plate, the lever or handle *b* is released and the spring *d* acts to automatically return and maintain the 35 said arm to and in the said position of safety. Thus the upper or vertically movable plate is held against falling by the lugs or brackets *c*, *c*¹, *c*², and the locked relationship between the arm or lever handle and the guide pillar 40 or support.

What I claim and desire to secure by Letters Patent is:—

1. In hydraulic and other presses, the combination with the upper movable plate, guide pillars therefor and the operating lever, of 45 brackets provided on the said plate for engaging the said lever and a spring carried by one of the said brackets, operatively related to the lever to admit of angular movement thereof and to automatically position 50 the said lever on the upper end of said guide pillars upon the attendant releasing the same after effecting the opening of the press.

2. In hydraulic and other presses, the combination, with the upper movable plate, guide 55 pillars therefor and operating lever, of lever engaging brackets whereof one is elongated and formed with an apertured depending part, a rod, secured to the lever and slidable through said depending part, a spring coiled 60 on the said rod and having one end acting against the lever and the other end against the said depending part of the bracket.

3. In hydraulic and other presses, the combination with the upper movable plate of 65 guide pillars therefor having their upper terminations at the level of the top of the press, an operating lever rotatably mounted in relation to the said plate and said guide pillars, stop brackets secured to the movable plate, a 70 laterally extending rod on said lever slidable in one of said brackets and a spring in said bracket for controlling the angular movement of the lever, whereby it is automatically brought to rest on the upper terminations of 75 the guide pillars.

In witness whereof I have hereunto subscribed my signature.

ERNEST SYDNEY.
